UNITED STATES PATENT OFFICE.

FRANCIS HOWARD ROBINSON, OF FORT WILLIAM, ONTARIO, CANADA.

SELF-LOCKING HINGE.

1,151,397.

Specification of Letters Patent. Patented Aug. 24, 1915.

Application filed April 1, 1915. Serial No. 18,626.

To all whom it may concern:

Be it known that I, FRANCIS H. ROBINSON, a citizen of the Dominion of Canada, and a resident of Fort William, in the District of 5 Thunder Bay, Province of Ontario, Canada, have invented a new and Improved Self-Locking Hinge, of which the following is a full, clear, and exact description.

This invention relates to hinges and to an 10 automatic or self-locking hinge, and has for an object to provide an improved construction whereby a door may be held by the hinge in an open or partially open position.

Another object in view is to provide a 15 hinge in which locking members are provided designed to be readily thrown into and out of operation in order to hold the door in an open position.

In the accompanying drawings:—Figure 20 1 is a side elevation of a hinge embodying the invention, the same being partially closed; Fig. 2 is similar to Fig. 1 with certain parts broken away; Fig. 3 is a section through Fig. 2 on line 3—3; Fig. 4 is a 25 section through Fig. 1 on line 4—4.

Referring to the accompanying drawings by numeral, 1 indicates a wall or support and 2 a door to which the leaves 3 and 4, respectively, are secured. In Fig. 3 the hinge 30 is shown in use as a butt hinge, though it is evident that the hinge could be used as a T-hinge without departing from the spirit of the invention. The leaves 3 and 4 are provided with barrels 5 and 6 which interlock so that the pintle pin 7 may be passed therethrough for connecting the leaves together. Connected with the leaf 3 are quadrants or locking bars 8 and 9. It is evident that one or more than 2 locking bars could 35 be used without departing from the spirit of the invention. The locking bars are each provided with notches or reduced portions 40 and 11. The bars 8 and 9 are preferably rigidly secured to the leaf 3 but are adapted 45 to freely pass through apertures in the leaf 4.

A sliding or locking plate 12 is connected with the leaf 4 by means of a pin 13, which 50 may be in the nature of a thumb screw and which operates in slot 14, whereby plate 12 may be locked in operative or inoperative position. Plate 12 is provided with apertures 15 and 16 through which the bars 8 and 9 freely pass when the plate is in the 55 position shown in Fig. 1. When plate 12 is lowered to the position shown in Fig. 2 the

slots 17 and 18 accommodate the reduced portion 11 or the reduced portion 10, as the case may be, and thereby lock leaf 4 and door 2 secured thereto against further movement. 60 It is evident that more than two reduced portions may be provided without departing from the spirit of the invention. When door 2 is closed the plate 12 is, of course, in its elevated position, as shown in Fig. 1, and the locking bars 8 and 9 are extended into suitable slots 19 formed in door 2, there being a slot 19 for each of the locking bars. 65

By forming the hinge with locking bars and a sliding locking plate as above set 70 forth, means are presented which will firmly hold the door in any desired position without the use of stops or other means acting on the door. Heretofore when an ordinary hinge has been used it is necessary to use a 75 chair, prop or some movable object in order to prevent the door from closing under the action of air pressure or any accidental movement given the door. The hinge above described presents means which will automatically hold the door in any position desired after the parts have been properly adjusted. In order to limit the opening of the door a head or enlargement 20 may be arranged on the outer end of the various 80 locking bars. 85

Having thus described my invention, I claim:—

1. In a hinge of the character described, a locking bar extending from one leaf to the 90 other, said locking bar being formed with a plurality of notches, said bar also being fixed to one of the leaves and arranged to extend through an aperture in the other of said leaves, a sliding locking plate arranged to fit in one of said notches according to the 95 adjustment of the leaves so as to lock the leaves against movement, and means for locking the plate against movement after the same has been adjusted. 100

2. In a hinge of the character described, a leaf, a plurality of locking bars connected with said leaf, each of said locking bars being formed with a plurality of notches and reduced portions, a second leaf, means for 105 pivotally connecting said second leaf with said first mentioned leaf, said second leaf having apertures through which said bars may pass, a locking plate arranged on said second leaf, said locking plate being provided with an aperture having a reduced 110 slot for each of said locking bars, whereby

the locking bar may freely pass through the locking plate when the plate is in one position and held against movement when the reduced extensions fit into said notches, and
5 a combined guiding and retaining member clamping said locking plate in position.

In testimony whereof I have signed my

name to this specification in the presence of two subscribing witnesses.

FRANCIS HOWARD ROBINSON.
